CHARACTER POSITIONING MEANS IN WIRE PRINTERS

Harold J. Kistner and Otto F. Moneagle, Endicott, N.Y., assignors to International Business Machines Corporation, New York, N.Y., a corporation of New York

Application November 23, 1955, Serial No. 548,736

12 Claims. (Cl. 101—93)

This invention relates to printers having an element positionable according to the character to be printed and more particularly to mechanisms for positioning the character determining element.

A printer of this type is disclosed in United States Patent No. 2,730,040, issued January 10, 1956, to Reynold B. Johnson. The wire printer disclosed therein has a code rod as a character pattern determining element which is positioned and then moved against the control ends of print wires prior to the printing impact undergone by the other ends of the differentially displaced wires to select the particular character to be printed. Such a code rod may be indexed axially to and from any of twelve index points and rotated angularly about its axis to and from any of four index points to provide forty-eight character determining positions. The positioning of such a code rod is under the control of six magnets, four of which, when energized singly or in combination, determine which of the twelve axial points other than the home point and two of which, when energized singly or in combination, determine which of the four angular points other than the home point that it will be disposed in. These magnets, upon energization, are effective through an adding linkage actuated by a pairs of cyclically operated bails to position the code rod once in each cycle.

A general object of this invention is to improve the speeds of printers and in particular those of wire printers. A more specific object of the invention is to provide a setup mechanism for a wire printer code rod which requires less time.

A further object of this invention is to provide such a setup mechanism which is also accurate and reliable in operation.

Still another object of the invention is to provide such a setup mechanism which is also easy of construction and inexpensive of manufacture.

According to the invention, a simple setup mechanism is provided for moving the code rod directly from position to position without necessitating return to a home position, thus enabling the shortening of machine cycles as the code will be positioned in less time than was heretofore attainable. The novel setup mechanism comprises two independent sets of wedges, each set of which has a one-way driving connection with the code rod. These wedge sets are alternately operated so that while preparation is being made to set one up, the other is being used to hold the code rod in a particular character setting. They are operated in alternation by a pair of alternately operable bails through a single set of magnets corresponding to the six magnets in the above identified application. Like those magnets, they may be energized once in each cycle singly or in combination according to the character to be printed. Unlike those magnets, and due to the alternate operation of the bails, they are effective upon the wedges of a set only once in every other cycle.

Other objects of the invention will be pointed out in

the following description and claims and illustrated in the accompanying drawings, which disclose, by way of examples, the principle of the invention and the best mode which has been contemplated of applying that principle.

In the drawings:

Fig. 1 is a front view, partially in section, disclosing a mechanism constructed according to the invention.

Fig. 2 is an enlarged view taken along the section line

10 2—2 of Fig. 1.

Fig. 3 is an enlarged view showing in perspective a portion of the apparatus shown in Fig. 1.

Fig. 4 is a schematic diagram of the electrical wiring employed in the invention.

15 Fig. 5 is a chart depicting the timing of various component parts of the invention.

Referring more particularly to the drawings, Fig. 1 discloses a code rod 10 which may be indexed axially to any of twelve points and angularly to any of four 20 points to provide a total of forty-eight different positions respectively determinative of forty-eight different characters. The code rod is mounted on the upper end of a flexible stem 12 which is driven at its lower end to index 25 the code rod while enabling the latter to be moved bodily against a plurality of print wires 14 to impart selective axial displacement thereto to determine particular character patterns.

Axial or translational movement is imparted to the stem and thus to the code rod through a collar 16 affixed 30 thereto near its lower end. This collar is embraced by the branches 18a and 18b (split to surround the stem 12) on the end of a lever 18 pivoted about a stud 20 fixed to a suitable support 22. The lower end of the stem has affixed to it an axially extending gear 24 which 35 meshes with a pair of reversely reciprocal racks 26 and 28. The ends of these racks are offset as at 26a and 28a and are pivotally connected at their offset ends to the upper and lower ends of a compound lever 30 mounted on a stud 32 fixed to the plate 22. It can be seen that 40 by rocking the lever 18 axial displacement will be imparted to the code rod and that by rocking the lever 30 to reciprocate the racks 26 and 28, angular movement will be imparted to the code rod.

Motion is imparted to the translation effecting lever 45 18 and to the rotation effecting lever 30 through a cross-over linkage. This cross-over linkage includes a link 34 pivotally connected at one end to an arm 36 projecting upward from the translation effecting lever 18 and at its other end to the upper end of a lever 38 mounted 50 forward of a guide bar 40 fulcrumed at an intermediate point 38a upon a guide bar-carried movable block 39 and pivotally connected at its lower end to a cross-over link 42. The other end of this cross-over link is pivotally connected to the lower end of a lever 44 disposed behind the bar 40 and fulcrumed at an intermediate point 45 upon a block 45 slidably carried upon the rear side of the guide bar 40. The upper end of this lever is pivotally supported upon a stud 46 fixed to the support 22.

The rotation effecting lever 30 has a pin and slot connection with the lower end of a compound lever 48 60 pivoted at an intermediate point on a stud 50 carried by the plate 22 and is pivotally connected at its other or upper end to the right-hand end of a link 52 disposed behind the link 34, as seen in Fig. 1. The other end of 65 this link is, like the forward link 34, pivotally connected to the upper end of a lever 54 disposed behind the bar 40 and fulcrumed at an intermediate point upon a block 55 slidably carried upon the rear side of the guide bar 40. The lever 54 is pivotally connected at its lower 70 end to a second cross-over link 56. This link crosses over the link 42 so that it may be pivotally connected at its other end to the lower end of a lever 58 disposed in front

of the guide bar 40 and engaging at an intermediate point a block 60 slidably mounted on the forward side of the guide bar. The lever 58 is pivotally mounted at its upper end on the stud 46 also mounting the lever 44. It can now be seen that outward movement of the left-hand front block 60 will swing the lever 58 clockwise about the stud 46 to pull on the link 56 and pivot the lever 54 about its fulcrum point with the block 55 to shift the link 52 to the right, as seen in Fig. 1, thereby imparting clockwise rotation to the lever 48 and counter-clockwise rotation to the compound lever 30. This will move the front rack 26 to the left and the rear rack 28 to the right to impart a clockwise rotation to the code rod 10 as seen from above. Similar rotation of the code rod results if the block 55 on the rear side of the guide bar 40 is moved outwardly as it will swing the lever 54 about its pivotal connection with the cross-over link 56 to shift the link 52 to the right. Hence, outward movement of either the front block 60 or the rear block 55 will achieve clockwise rotation of the code rod.

Outward movement of the rear block 45 will swing the lever 44 about its pivotal mounting on the stud 46 to exert a pull on the cross-over link 42 rotating the lever 38 clockwise about its fulcrum point with the front block 39 to shift the front link 34 to the right to rotate the lever 18 clockwise and move the code rod 10 downward. Outward movement of the front block 39 will achieve similar results by swinging the lever 38 about its point of connection with the cross-over link 42 to shift the link 34 to the right. It follows that, if either the rear block 45 or the front block 39 is allowed to move inwardly, the link 34 will be shifted to the left due to the forces imposed by the spring 62 upon the upper end of the code rod and acting through the collar 16 to raise the lever 18 and shift it clockwise, thus forcing the link 34 to the left. In this case, the positioning of the code rod will be determined by the amount of movement that the spring is allowed to impart to one or the other of the movable blocks 39 and 45. The positioning of these movable blocks is controlled by sets of wedges generally indicated by the letter W.

The sets of wedges are mounted upon the front and rear sides of the guide bar 40, respectively. Referring more particularly to Figs. 1 and 3, each set of wedges may be seen to be comprised of six wedges W separated by small rollers 64. Other such rollers 64 are also provided to separate the end wedges from the corresponding slidable blocks such as 60 and 39. To enable the code rod to be shifted to any of twelve axial displaced points, four wedges are employed having the respective values of +4, +2, +1, and -5, as is shown in Fig. 1. Thus, the +4 wedge will impart four increments, the +2 wedge two increments, the +1 wedge one increment, and the -5 wedge five negative increments of displacement to the code rod when raised so that the high points of their cam surfaces are opposite the rollers. The rollers are held against vertical displacement by the flanges 40a and 40b at the top and bottom edges of the guide bar 40 and by an intermediate raised track 40c. In undergoing raised movement, the wedges not only displace themselves and the exteriorly disposed rollers and wedges with respect to the more interiorly disposed rollers but also impart additional displacement to the exteriorly disposed rollers and wedges due to the cam action on the exterior side of the wedge. It will be evident that the displacement obtained by raising various combinations of these wedges may be such as to raise the code rod to any of five plus points from a home point as when the -5 wedge is raised singly or in combination with any one or more of the three plus wedges and to lower the code rod to any of six points from the home point when any one or more of the plus wedges are raised.

Two wedges are employed in each unit to effect angular displacement of the code rod. These wedges have the

respective values of +2 and +1 and are similar in action to the wedges for effecting axial displacement of the code rod. Suffice it to point out here that the +1 wedge rotates the code rod one point in the clockwise direction, as viewed from above, from the home position and that the +2 wedge imparts two points of clockwise rotation while a combination of the two wedges imparts three points of such rotation. The wedge units of each set, that is, the wedges for imparting axial displacement and the wedges for imparting angular displacement to the code rod, are prevented from interfering with one another by firmly securing the rollers separating the -5 wedge in the axial displacement unit and the +1 wedge in the angular displacement unit to the guide member, as by welding. Thus, these two rollers merely serve as bearing surfaces for the adjacent wedges.

On the back side of the guide bar 40, the disposition of the wedges is reversed from right to left. Thus, the +4 wedge of the axial displacement unit lies behind the +2 wedge of the angular displacement unit on the front side, whereas the +2 wedge of the angular displacement unit on the rear side lies behind the +4 wedge of the axial displacement unit on the front side. This is necessary because the levers at one end of the guide bar are interconnected with the levers disposed on the opposite sides at the other end of the bar by the cross-over links 42 and 56, as has been pointed out.

It has also been pointed out that the wedges are effective upon upward displacement to impart lateral motion not only to themselves but also to the slidable blocks associated with the corresponding wedge unit. The wedges themselves are slidably mounted in the offset portions 66a (Figs. 2 and 3) of corresponding operating arms 66 so as to be carried upwardly when the arms are displaced upwardly and yet to be movable laterally when undergoing cam action during such vertical displacement or as a result of a coacting wedge having been raised.

Upward displacement of the respective operating arms 66 (Figs. 1 and 2) is effective through pawls 68 pivotally affixed to their upper ends. These pawls cooperate with lugs 70 projecting laterally from the surfaces of vertically reciprocable baits 72A and 72B. If a pawl is released while the associated bait is in the downward position, the pawl rotates, under the action of a spring 74 affixed at its lower end to an ear 66b of the corresponding operating arm, to where a laterally extending part 68a of the pawl rests upon a corresponding laterally projecting ear 76 carried by the associated bait. In this position the pawl is disposed over the corresponding lug 70, and when the bait moves upwardly, the lug carries the pawl and hence the corresponding operating arm upwardly. This imparts an upward displacement to the corresponding wedge which then operates in the manner heretofore explained to index the code rod.

The restoration of a pawl from in front of a lug 70 is effected during the subsequent downward movement of the bait. A latch 78, pivotally mounted at an intermediate point on a stud 80 affixed to the plate 22, is connected at its lower end to a tension spring 82 which urges the upper end of the latch into the downward path of the laterally extending part 68a of a corresponding pawl. Thus, when a raised operating arm 66 is lowered due to the engagement of the corresponding lug 70 on the lowering bait with a shoulder 66c on it, the part 68a of the corresponding pawl strikes this latch and rotates the pawl out of the path of the corresponding lug 70. This prevents subsequent upward movement of the operating arm when the bait again moves upward unless the latch 78 is again rotated from beneath the laterally extending part of the pawl to dispose the pawl again in the path of the corresponding lug. By selectively controlling the latches 78, the code rod 10 can be positioned in different character settings.

Each latch is controlled by a corresponding magnet 84

suitably supported on the frame 22. Each magnet is provided with an armature 86 pivoted on a stud 88 and having a depending arm which is engaged by the corresponding latch. Upon energization of a magnet, the corresponding armature is rocked to rock the latch about its pivot point and release the corresponding pawl 68 for movement into the path of the corresponding lug 70. In this way discrete electrical impulses will be translated through the mechanical operation of the bails 72A and 72B into a particular positioning of the code rod. It may be noted that a spring 82 biasing the corresponding latch 78 to the pawl intercepting position also operates upon the armature to move it away from the magnet and that the ultimate position of an armature and its latch is determined by a stop 90 mounted on the associated magnet 84.

It may also be noted at this time that the energization of a magnet has no effect upon the pawl for the bail that is in a raised position. This is because the withdrawal of the latch from beneath the pawl is not followed by a rotation of the pawl under the influence of its spring 74 due to the fact that the pawl engages the side of the corresponding lug 70 which is now in a raised position relative to it. Hence, when the magnet is deenergized the laterally extending arm 68a of the pawl is still above its corresponding latch and allows the latch to move thereunder again to prevent the pawl from rotating into the path of the lug 70 when the bail reaches a lowered position.

The operation of the device will now be described with particular reference to the timing chart of Fig. 5. As is shown therein, the operating bails 72A and 72B continuously reciprocate up and down 180° out of phase with each other, traveling between a high and low point once in each cycle and completely restoring once in every other cycle. The magnets are pulsed just before the raise time for each operating bail to dispose the corresponding pawls 68 in the path of the lugs 70 affixed to the lowered bail, specifically bail 72A in Fig. 1. Thus, the magnets will be pulsed the next time while the information represented by the previous set of pulses is being represented by a mechanical displacement of the code rod 10, and it may be further observed from the timing chart that the displacement of the code rod will be fixed for the greater portion of a cycle due to the fact that the high portions of the cam surfaces of the wedges W remain opposite the corresponding rollers 64 even though the wedges themselves continue to move upward and then downward for some time. This allows sufficient time for the setup or positioned code rod to be moved, as by the cams 92 shown schematically in Fig. 1, against the control ends of the print wires 14 prior to the making of printing impact with their other or print ends.

It is evident from a consideration of Fig. 1 that the magnets 84 bearing the further designation of *a*, *b*, *c*, and *d* control the operation of the axial displacement wedge unit in the front set of wedges while the magnets *e* and *f* control the operation of the angular displacement wedge unit therein and that, for the rear set of wedges, the magnets *f*, *e*, *d*, and *c* control the wedges in the axial displacement wedge unit while the magnets *b* and *a* control wedges in the angular displacement wedge unit. This entails an electrical switching arrangement to change the magnets which will be energized by the combinations of discrete electrical impulses when the different operating bails are about to be raised.

Fig. 4 shows such an electrical switching arrangement. There the magnets *a* through *f* are shown as being connected through normally closed contacts C1 through C6 to corresponding wires 84 leading from a data source DS. This is the condition which obtains for every other cycle and, in particular, when the data is to be translated by the rear bail 72B into a mechanical displacement of the code rod. In the other or alternate cycles, the connections between the wires 94 leading from the

data source DS and the magnets 84 are reversed. This may be effected by closing a set of cam contacts 96 to energize a switching relay 98 controlling the contacts C1 through C6 for the respective setup magnets. Thus, when the switching relay is energized, the common straps of the transfer contacts C1 through C6 are shifted to close the normally open contacts to operate the *f*, *e*, *d*, *c*, *b*, and *a* magnets when formerly the *a*, *b*, *c*, *d*, *e*, and *f* magnets, respectively, were energized. It can now be seen that there has been provided a unique arrangement wherein one set of magnets may be energized in successive cycles to move the code rod directly from one character determining position to another and without necessarily passing through the home position located at an intermediate point, though such movement may occur.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

25 What is claimed is:

1. In a mechanism; a part having a normal position and disposable in any of a number of positions; a plurality of wedges respectively movable between normal and second positions, means serially, drivingly connecting said wedges to said part and operable by respective ones of said wedges when they are moved from normal to second positions to dispose said part in positions having corresponding increments of cumulative displacement from the normal position; a cyclically operable bail reciprocable between first and second positions; and selectively actuatable means for the respective wedges operable when actuated to connect the corresponding wedge to the bail for movement from the normal to the second position.
2. In a mechanism; a part disposable in any of a number of positions; a first set of wedges in which the wedges are serially, drivingly connected to said part and respectively operable when moved from a first to a second position to impart cumulatively corresponding increments of displacement to said part to dispose it in a corresponding position; a second set of wedges in which the wedges are serially, drivingly connected to said part and respectively operable when moved from a first to a second position to impart cumulatively corresponding increments of displacement to said part to dispose it in a corresponding position; cyclically operated bails for the sets of wedges reciprocable between first and second positions and in out-of-phase relationship; and a selectively actuatable means for corresponding wedges in each set of wedges respectively operable when actuated to drivably connect the corresponding wedges to the reciprocable bail then at the first position for movement from their normal to their second positions.
3. In a mechanism; a part movable to a second point in one direction and to a second point in another direction; two sets of wedges, each set including a first wedge drivingly connected with said part and operable when moved from a normal to a second position to move said part to the second point in the one direction and a second wedge drivingly connected with said part and operable when moved from a normal to a second position to move said part to the second point in the other direction, cyclically operated bails for the respective sets of wedges reciprocable between first and second positions and in out-of-phase relation, and selectively actuatable means for corresponding wedges in each set of wedges operable when actuated to connect drivably the wedge corresponding to the bail that is at that time at the first position thereto for movement from the normal to the

second position as the bail moves from the first to the second position.

4. In a mechanism, a part movable to a second point in one direction and to a second point in another direction from a home position, two sets of wedges, each set having one-way driving connections with said part and including a first wedge operable when moved from a normal to a second position to move said part to the second point in the one direction and a second wedge operable when moved from a normal to a second position to move said part to the second point in the other direction, cyclically operated bails for the respective sets of wedges and reciprocable between first and second positions and in 180° phase relation, and selectively actuatable means for corresponding wedges in each set of wedges operable when actuated to connect the corresponding wedge to the corresponding bail that is at the first position at that time for movement from the normal to the second position as the bail moves from the first to the second position.

5. In a mechanism for translating a code rod axially to any of a number of different points and rotating it about its axis to any of a number of different points, two sets of wedges each comprised of two units of wedges, each unit of wedges including an end block and a plurality of wedges serially connected and operable when moved from a normal to a second position to impart different cumulative increments of lateral displacement to the corresponding block, said sets of wedges being in side by side relationship, levers for each of the blocks at one end of said sets of wedges pivotally mounted at one end on a fixed stud and fulcrumed at intermediate points upon the corresponding blocks, levers for each of the blocks at the other end of said sets of wedges and fulcrumed at intermediate points thereon, cross-over links interconnecting the free ends of the levers at one end of said sets of wedges with the free ends of the levers of the opposite set at the other end of said sets of wedges, linkage for connecting the other free end of one of said levers at the other end of said sets of wedges with a code rod to impart translational displacement thereto, other linkage connecting the other free end of the other of said levers at the other end of said sets of wedges to impart rotational displacement to a code rod, cyclically operated bails for the respective sets of wedges reciprocable between first and second positions and in 180° phase relation, and selectively actuatable means for corresponding wedges in each of said sets of wedges operative when actuated to connect drivenly the wedge corresponding to the bail at that time at the first position to the bail for movement from the normal to the second position as the bail moves from the first to the second position.

6. In a mechanism for imparting a fixed increment of displacement to a part, a wedge movable between a normal and a second position, means operable when the wedge is moved from a normal to a second position to impart a fixed increment of displacement to such a part, an arm movable between normal and second positions and carrying said wedge, said wedge being operative when the arm is moved to its second position to move the wedge from the normal to the second position and relative to said arm, a driving element movable through a fixed range of movement, and means operative to connect said arm to said element for movement of the arm from its normal to its second position.

7. In a mechanism, a member movable from a first to a second position, a bail reciprocable between a first and a second position, a pawl mounted on said member and biased for disposition in the path of said bail, a latch biased to a position in which it holds the pawl out of engagement with the bail when the member is in the first position, means operable to move said latch away from said pawl to permit the latter to move into the path of said bail when the latter is in the first position.

tion, means for automatically returning said member to the first position after it has been moved to the second position, said latch being effective when released by said means prior to the movement of the member from the second position to the first position to intercept the pawl in its biased position and restore the same out of the path of the bail.

8. In a mechanism, a member movable from a first to a second position and having a shoulder, a bail reciprocable between a first and a second position and having a lug disposed for cooperation with the shoulder on the member, a pawl mounted on said member and biased to a position in which it lies in the path of said lug and drivenly connects the member to the bail for movement from the first to the second position as the bail moves from the first to the second position, a latch biased to a position in which it holds the pawl out of the path of said lug, means operable to move said latch away from said pawl to permit the latter to move into the path of said lug when the bail is in the first position, said lug being effective to restore the member from the second position to the first position as the bail moves from the second position to its first position, said latch being effective when released by said means prior to the movement of the member from the second position to the first position to intercept the pawl in its biased position and restore the same out of the path of the bail, said lug being so disposed as also to prevent biased movement of the pawl when the latch is operated at a time other than when the bail is at the first position.

9. In a mechanism, a member movable from a first to a second position and having a shoulder, a bail reciprocable between a first and a second position and having a first lug disposed for cooperation with the shoulder on the member and a second lug, a pawl mounted on said member and biased to a position in which it is stopped by said second lug and lies in the path of said first lug to drivenly connect the member to the bail for movement from the first to the second position as the bail moves from the first to the second position, a latch biased to a position in which it holds the pawl out of its biased position, means operable to move said latch away from said pawl to permit the latter to move to its biased position, said first lug being effective to restore the member from the second position to the first position as the bail moves from the second position to its first position, said latch being effective when released by said means prior to the movement of the member from the second position to the first position to intercept the pawl in its biased position and restore it, said lug being so disposed as also to prevent biased movement of the pawl when the latch is operated at a time other than when the bail is at the first position.

10. In a mechanism, two members each movable from a normal to a second position and having a shoulder, cyclically operated bails for the corresponding members reciprocable between first and second positions and in 180° phase relation and each bearing a lug adapted to engage the shoulder of the corresponding member and move the member from the second to the first position if the member was moved to the second position as the bail moves from the second to the first position, a pawl mounted on each of said members and biased to a position in the path of the lug on the corresponding bail to drivenly connect the member to the bail for movement from its first to its second position as the bail moves from its first to its second position, a latch operative upon both of said pawls to hold them out of engagement with the corresponding lugs, means operable to release said latch at those times that the different bails are at their first position, said lugs being so formed as to prevent the biased movement of the corresponding pawl when that bail is at other than its first position.

11. In a mechanism, a part disposable in a plurality of positions, a pair of wedges each disposable in two posi-

tions, means constituting a one way driving connection from a first one of said wedges to said part and operable when said first wedge is moved from a first one of its said positions to a second one of its said positions to move said part from a first one of said part positions to a second one of said part positions, means constituting a one way driving connection from the second one of said wedges to said part and operable when said second wedge is moved from a first one of its said positions to a second one of its said positions to move said part from said first part position to said second part position, a bail for each wedge, each bail reciprocable between two positions and cyclically operated so that one is at a first one of said bail positions when the other is at the second one of said bail positions, selectively actuatable means for connecting each bail to the associated wedge, and means for selec-

10

tively actuating said connecting means when said bail and said wedge are in their first said positions.

12. The device described in claim 11 wherein the driving connection means associated with said first wedge causes said part to move in a first direction, and the driving connection means associated with said second wedge cause said part to move in a second direction.
